Primary Examiner — Susan E Krakower*Assistant Examiner* — Christina M. Dodson(74) *Attorney, Agent, or Firm* — Jose Cherson Weissbrot(57) **CLAIM**

The ornamental design for a starry sky projection light, as shown and described.

DESCRIPTION

FIG. 1 is a front, right, top perspective view of a starry sky projection light, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 2;

FIG. 11 is an enlarged view of detail 11 in FIG. 3; and,

FIG. 12 is an enlarged view of detail 12 in FIG. 8.

The dashed broken lines in the figures illustrate portions of the starry sky projection light that form no part of the claimed design.

The dash-dot-dash broken lines illustrate the boundaries for the enlarged views and form no part of the claimed design.
